(57) **CLAIM**

The ornamental design of an accessory port adaptor with
bracket mount, as shown and described.

DESCRIPTION

FIG. 1 is a perspective view of the accessory port adaptor
with bracket mount of the present invention;
FIG. 2 is a front elevational view thereof;
FIG. 3 is a rear elevational view thereof;
FIG. 4 is a right side elevational view, the left side eleva-
tional view being a substantial mirror image thereof;
FIG. 5 is a top plan view thereof; and,
FIG. 6 is a bottom plan view thereof.
